UNITED STATES PATENT OFFICE.

FRED N. LANG, OF BAYFIELD, WISCONSIN.

ADHESIVE PLASTER.

1,081,392.

Specification of Letters Patent.

Patented Dec. 16, 1913.

Application filed December 13, 1912. Serial No. 736,548.

To all whom it may concern:

Be it known that I, FRED N. LANG, a citizen of the United States, residing at Bayfield, in the county of Bayfield and State of Wisconsin, have invented new and useful Improvements in Adhesive Plasters, of which the following is a specification.

This invention relates to medicines, and more particularly to an improvement in adhesive plasters.

Adhesive plasters as a rule are made with a close woven or waterprrof fabric backing, one side of which is provided with a layer of medicated adhesive material, and to prevent the adhesive surface from sticking to articles until ready for use generally a piece of thin cloth or gauze is applied over the adhesive side. Experience has shown that a plaster of this kind in warm weather, or when subjected to heat from any cause, will deteriorate as the medicated surface has the tendency to stick to the gauze or cloth covering and soak into it thereby losing a part of its value. Another feature of the cloth or gauze covering is that in some cases it is very difficult to remove the covering from the plaster and in other cases where the plaster is put up in large strips, but is intended to be cut out as needed, for instance, as corn plaster, it is necessary to cut both plaster and covering together and in such cases it is very difficult to remove the gauze or cloth covering without deforming the shape of the cut out piece.

It is the object of this invention to provide a covering for the adhesive side of the plaster to which it will adhere sufficiently to be retained thereon and at the same time the covering will protect the medicated portion from deteriorating and will allow the plaster to be easily removed, and also allow the plaster to be cut in the shape desired for use and removed easily without deforming the cut out shape.

The advantages of this invention are obvious. Plasters of this character may be kept in stock without fear of deterioration, they may be carried about under all conditions without becoming sticky and not only easily removed from the covering, but are also always ready to apply in perfect condition.

While the preferred forms of this invention are illustrated upon the accompanying sheet of drawing, yet it is to be understood

that minor detail changes may be made without departing from the scope thereof.

Figure 1 is a top plan view of an adhesive plaster provided with a covering as contemplated in this invention. Fig. 2 is a view in perspective illustrating the cutting of a small size piece of the plaster and removing the same as contemplated in this invention. Fig. 3 is a view in longitudinal vertical section through the plaster and cover as illustrated in Fig. 1.

In the usual form of adhesive, medicated plaster the medicated adhesive side of the plaster is covered by a piece of cloth or gauze. In Fig. 1, the plaster 1 is illustrated with its medicated side adhering to the impervious, hard, substantially solid covering 3 as contemplated in this invention. Of the different impervious, hard, substantially solid materials a thin piece of aluminium is preferable for this covering, as this metal has a somewhat greasy surface that allows the plaster to adhere sufficiently to act as a covering, but will not stick, even when submitted to considerable heat, so as to cause difficulty in removing and is of sufficient hardness to allow a piece of any desired size or shape to be cut out of the body of the plaster by a penknife and readily removed from the covering without deforming the shape of the piece or cutting through the covering, as illustrated in Fig. 3. Aluminium is also preferable on account of its light weight and pliability which are both advantageous in packing, storing and shipping, however, other metals or cardboard having a varnished or painted side upon which the medicated, adhesive surface might be applied will also answer the purposes of this invention.

What I claim is:

1. In a plaster, the combination with an adhesive surface, and a covering therefor upon which portions of the plaster may be cut and easily removed from the covering without cutting through the covering.

2. A plaster having an adhesive surface and a hard, impenetrable substantially solid covering therefor.

3. A plaster having an adhesive surface and a covering therefor of aluminium.

FRED N. LANG.
